UNITED STATES PATENT OFFICE.

MOSES ALSHULER, OF MATTOON, ILLINOIS.

TAG.

SPECIFICATION forming part of Letters Patent No. 341,205, dated May 4, 1886.

Application filed September 10, 1884. Serial No. 142,574. (No model.)

To all whom it may concern:

Be it known that I, MOSES ALSHULER, of Mattoon, in the county of Coles and State of Illinois, have invented certain new and useful Improvements in Tags; and I do hereby declare that the following is a full, clear, and exact description thereof, reference being had to the accompanying drawings, and to the letters of reference marked thereon, which 10 form a part of this specification.

This invention relates to an improvement in price-tags and fasteners or holders therefor, and more particularly to that class of tags which are secured to the cloth by means of a 15 spiral fastener—such, for instance, as is illustrated in an application for a patent made by me upon the 11th day of February, 1884, and now pending.

The tag herein illustrated is more especially 20 intended for attachment to the surface of goods in such manner as to lie flat thereon.

The fastening device for the said tag consists of a spirally-coiled pin or fastener provided with a head at one end—such as is described and shown in the application above referred to—which is used in connection with a tag made of two separate layers of paper, through one only of which the point of the fastener is inserted, the tag being secured to 25 the cloth by passing the fastener first through the cloth and then into the tag, in an obvious manner. The coiled portion of the pin is preferably cone-shaped and formed of flexible wire, so that the coils thereof may be bent into 30 the same plane, and will lie flat between the layers of paper composing the tag when inserted between the latter. The object of this construction in the tag and fastener is to cover the point of the spiral pin when the tag is 35 fastened to the cloth, and also to provide a smooth surface upon the side of the tag opposite to that which is in contact with the cloth, upon which the necessary designating marks or figures may be placed.

40 The tag formed of two layers, as above described, may consist of two separate layers of paper secured together at their margins and unattached at their central portions, so that the layers may separate to allow the free entrance of the spiral coil between them, the 45 lower layer usually being provided with a cen-

tral aperture, through which the point of the pin is inserted. The layer through which the pin is inserted may, however, be made of paper of a comparatively soft and spongy nature, 55 so that the end of the coil will readily penetrate it, and in such case the layers may be pasted at their edges only, so as to form a central free space, as before mentioned; or the layers may be pasted together throughout 60 their entire area, and the spiral portion of the pin allowed to insert itself in the soft or spongy layer, the relative hardness of the upper layer or outer face of the tag in the latter case obviously serving to prevent the point 65 of the pin from passing into said outer layer.

In the accompanying drawings, Figure 1 is a sectional perspective view of a tag consisting of two layers of paper, showing a fastener applied to secure such tag upon the cloth. Fig. 70 Fig. 2 is a perspective view of a fastener detached from the tag. Fig. 3 is a central vertical section through the tag illustrated in Fig. 1, and the cloth to which such tag is attached.

A is the tag-fastener, which consists of wire 75 bent in a spiral form and provided with a head, a, at one end, and sharpened to form a point at its opposite end. The head a may be made in any well-known or desired manner.

In the form of the device illustrated in Figs. 80 1 and 3, the head consists of a small knob, button, or disk attached to or formed upon the end of the wire, and, as illustrated in Fig. 2, the said head is formed by a small coil upon the end of the wire composing the fastener. 85

The tag B consists of a flat layer, B', of paper having a suitably-hard surface for marking with pencil or pen, and a second layer, B'', preferably secured at its edges only to the part B', so as to form the centrally-open space, into 90 which the spiral part of the pin A may freely enter, having been inserted through the layer B''. The said layer B'' may be desirably provided with a central aperture, b, to freely admit the point of the pin in securing the tag; 95 but such aperture is obviously not necessary, inasmuch as said layer B'' may be formed of paper of a relatively soft or spongy nature, so that the point of the pin may be readily inserted through it. A form of the coil in which 100 the latter is of conical shape, as illustrated, is preferred, in order that when the coil is in-

serted between the layer composing the tag they may be bent into the same plane, so as to form a flat spiral, as clearly shown in Fig. 1.

In order to enable the tag to be drawn and held closely against the surface of the cloth, the spiral fastening is preferably coiled in a continuous curve from its head to its point, or, in other words, any straight part or shank adjacent to the head is absent, so that after the point of the pin is inserted through between the layers of paper composing the tag the latter may be drawn closely against the surface of the cloth by turning the fastener until the greater portion of the coil has entered the tag.

The layer B², when of a soft or spongy nature, need not necessarily be unattached in its central portions to form a central open space for the entrance of the fastener, as above described; but the layers may be pasted together throughout their entire area, and the spiral coil permitted to embed itself in the spongy paper adjacent to the surface of the harder layer, B'.

In the operation of inserting the fastener, when constructed as last mentioned, the point of the pin, after passing through the soft layer

B², encountering the relatively-hard layer B', comprising the imperforate front face of the tag, will obviously be unable to penetrate said hard layer, but will be deflected thereby and remain in the soft layer.

I claim as my invention—

1. A tag and fastener therefor, consisting of a spirally-coiled fastener pointed at one end and provided with a head at its opposite end, and a tag formed of two joined layers of paper, the inner one of which is adapted, substantially as described, for the insertion of the point of the pin.

2. The combination, with a spirally-coiled fastener pointed and provided with a head, of a tag consisting of two layers of paper secured together at their edge only, the inner of said layers being provided with an aperture to admit the point of the fastener, substantially as described.

In testimony that I claim the foregoing as my invention I affix my signature in presence of two witnesses.

MOSES ALSHULER.
